UNITED STATES PATENT OFFICE.

WILLIAM B. WILLIAMS, OF GREENVILLE, SOUTH CAROLINA.

WHIP-ROLL FOR LOOMS.

1,358,668.

Specification of Letters Patent.

Patented Nov. 9, 1920.

Application filed March 19, 1920. Serial No. 367,069.

To all whom it may concern:

Be it known that I, WILLIAM B. WILLIAMS, a citizen of the United States of America, and a resident of Greenville, county 5 of Greenville, and State of South Carolina, have invented certain new and useful Improvements in Whip-Rolls for Looms, of which the following is a full and clear specification.

10 The object of this invention is to provide simple means whereby the whip-roll supporting-arms may be readily repaired after their bearings have become so worn as to be more or less useless, as more fully herein- 15 after set forth.

In the drawings—

Figure 1 is a side elevation of a whip-roll supporting-arm provided with my repair-bearing;

20 Fig. 2 is a plan view thereof;

Fig. 3 is a side elevation of a common form of supporting-arm, as it appears before the bearings are worn.

The whip-roll is shown at *a*, one of its 25 supporting-arms at *b* and its oscillating supporting-shaft at *c*, these being constructed as usual. One of the arms for supporting the shaft *c* is shown at *d*, this arm being of the usual construction except that 30 the bearing for supporting the shaft *c* is made in accordance with my invention. The usual construction of this arm *d* before it is worn is shown in Fig. 3. It will be observed that it is provided with two bearing-notches *e*, *e'*.

35 In use, the outer bearing *e* wears away, as shown by dotted line *f*, thus destroying the utility of the entire arm and requiring that it be taken off the loom and discarded and replaced by a new arm. With my invention, I can utilize 40 this arm notwithstanding the fact that the bearing is worn to the extent of becoming useless as a support for the rock-shaft *c*.

In utilizing this worn arm, I mill away the 45 transverse rig *g* upstanding between the two bearing-notches, this being milled down to the dotted line *h*. I then fit into this widened notch a wooden block *i* and fasten the same in said notch by means of a 50 vertical bolt *j* which passes down through the block and through an opening in the arm bored for the special purpose of receiving this bolt. This block *i* is provided with a rounded notch *k* which forms a new bearing for the rock-shaft *c*. In this rounded 55

notch is formed a depression *l* which is adapted to be filled with tallow or some other material which will not only lubricate the bearing but will work into the body of the block and thus render the same virtually self-lubricating. Of course, the tallow deposit is renewed from time to time, but, as the wood becomes more and more impregnated with the tallow, a lesser quantity is required for proper lubrication.

With my invention, it will be obvious that I save the waste heretofore involved in junking the worn arms *d*. As the bearings in these arms wear quite rapidly, this is a very material saving, and particularly because of a fact which I have found from experience, namely, that the new or repair bearing lasts much longer than the original bearing and also results in lighter running of the whip-roll mechanism. The whip-roll-shaft *c* of course also becomes worn at the points of impingement against the bearing-arms, but I can bring a new surface into contact with the wooden bearing-blocks by swapping whip-rolls from one loom to another and reversing them, and thus aid materially in prolonging the life of the whip-roll mechanism and also prevent the worn-down surfaces of the shaft *c* from cutting the wooden blocks.

The nature and scope of the invention having been thus indicated and its preferred embodiment having been specifically described, what is claimed as new is:

1. In a whip-roll mechanism for looms, a supporting-arm for the whip-roll-shaft having a widened notch in its upper side, a wooden block fitted into this notch, said block being provided with a bearing-notch for receiving the shaft of the whip-roll and said notch being provided with a depression for receiving a lubricant, and a bolt for attaching the block to the arm.

2. In a loom, a whip-roll-arm provided with a notch, a wooden block fitted snugly in said notch and provided with a bearing-notch, and means for fastening this block in its seat.

In testimony whereof I hereunto affix my signature.

WILLIAM B. WILLIAMS.
